E. DOWNING.

AUTOMOBILE TIRE RACK.

APPLICATION FILED JAN. 2, 1917.

1,233,325.

Patented July 17, 1917.

Inventor
Edward Downing
By his Attorney
James Hamilton

UNITED STATES PATENT OFFICE.

EDWARD DOWNING, OF SAN FRANCISCO, CALIFORNIA, ASSIGNOR TO HOOVER SPRING CO., OF SAN FRANCISCO, CALIFORNIA, A CORPORATION OF CALIFORNIA.

AUTOMOBILE TIRE-RACK.

1,233,325.

Specification of Letters Patent. Patented July 17, 1917.

Application filed January 2, 1917. Serial No. 140,016.

To all whom it may concern:

Be it known that I, EDWARD DOWNING, a citizen of the United States of America, residing at San Francisco, in the county of 5 San Francisco and State of California, have invented certain new and useful Improvements in Automobile Tire-Racks, of which the following is a specification, reference being had to the accompanying drawings.

10 This invention relates to improvements in automobile tire-racks and particularly to improvements in the tire-racks described and shown in United States Patent No. 1,150,696 granted Llewelyn Arthur Nares 15 August 17, 1915, and United States Patent No. 1,197,272 granted me September 5, 1916; and an object of this invention is to simplify and to cheapen the construction of the tire-racks disclosed in the above-named patents 20 and to make them more efficient in operation.

In the drawings illustrating the principle of this invention and the best mode now known to me of applying that principle, Figure 1 is a front elevation of the tire-rack (or tire-carrier, as it is sometimes called); Fig. 2 is a section on the line 2—2 of Fig. 1; and Fig. 3 is a side elevation of the tire-carrier, looking in the direction of the arrow A of Fig. 1.

25 The base-ring *a* (as in the case of my patent hereinbefore referred to) is formed with an outwardly-projecting lip or flange *b*, to which there is fastened a pair of arm-hangers *c*. Diametrically opposite the latter, 30 there is fastened, to the inside of the ring *a*, a stationary tire-supporting arm *d*. By means of a pivot-pin or hinge-pin *c'*, there 35 is hingedly connected to the pair of arm-hangers *c*, the inner end of a swinging-arm 40 *e*.

As is clearly disclosed in Fig. 2, the hinge-pin *c'* lies outside of the base-ring *a*; and, when the arm *e* is swung into working or locking position, it is arrested and its outer travel is limited by the ring *a*. To 45 swing the arm *e* on its pivot-pin *c'*, there is provided a pair of toggle-links *f, f'*, of which the link *f'* is hingedly connected, at its outer end, to the swinging arm *e* by a pin *g* that lies within the outer end thereof, which end 50 is formed with an outwardly-turned lip *e'*. The other link *f* is connected by a hinge-pin

g' to a hinge-bracket *g''* that is fastened to the base-ring *a* together with the inner end of the stationary arm *d*. About midway and on the outside of each of the arms *d, e*, there 55 is fastened a tire-separator *h* formed with flanges *h', h''*, which, together with the flange *b* and lips *d', e'*, serve as stops or rests for the tires *h*. The arm *e* is provided with facing-pieces *e''* of canvas-like material. The toggle-link *f* is bifurcated at its inner end and, between branches *f''* of this forked end, there is held, by a lock *i*, the inner end *f''* of the toggle-link *f'*. When the lock *i* is removed and the toggle-links *f, f'*, 65 are swung inwardly, their inner ends *f'', f''*, turn on the pivot-pin *j*. The stationary tire-supporting arm *d* is stiffened or braced by means of the inclined braces *k*. The tire-rack may be mounted by fastening the base- 70 ring *a* to the bracket *m* carried by the vehicle-body *n*.

By hinging the outer end of the toggle-link *f* to the stationary tire-supporting arm *d*, the construction of the tire-rack is simplified and cheapened, as compared with the construction described in my patent hereinbefore referred to.

I claim:

1. An automobile tire-rack including a 80 base-ring; a stationary tire-supporting arm carried thereby; a swinging tire-engaging arm pivotally fastened to said base-ring; and a pair of toggle-links the outer end of one of which is pivotally connected to said base-ring and the outer end of the other of which is pivotally fastened to said swinging arm.

2. An automobile tire-rack including a 90 base-ring; a stationary tire-supporting arm carried thereby; a swinging tire-engaging arm pivotally fastened to said base-ring; and a pair of toggle-links the outer end of one of which is pivotally fastened to said stationary arm and the outer end of the other 95 of which is pivotally fastened to said swinging arm.

3. An automobile tire-rack including a 100 base-ring; a stationary tire-supporting arm carried thereby; a swinging tire-engaging arm pivotally fastened to said base ring; and a pair of toggle-links the outer end of

one of which is pivotally connected to said base-ring and the outer end of the other of which is pivotally fastened to the inner face of said swinging arm within the outer end thereof.

Signed at San Francisco, in the county of San Francisco and State of California, this

18th day of December, A. D. 1916, in the presence of the two undersigned witnesses.

EDWARD DOWNING.

Witnesses:

B. WILSON,
GARETH DOWNING.
